UNITED STATES PATENT OFFICE.

WILLIAM E. SURFACE, OF DECATUR, ILLINOIS, ASSIGNOR TO FARIES MANUFACTURING CO., OF DECATUR, ILLINOIS, A CORPORATION OF ILLINOIS.

DESIGN FOR A HANGER FOR LIGHT-REFLECTING BOWLS.

48,207.

Specification for Design.

Patented Nov. 23, 1915.

Application filed April 12, 1915. Serial No. 20,975. Term of patent 7 years.

To all whom it may concern:

Be it known that I, WILLIAM E. SURFACE, a citizen of the United States, residing at Decatur, in the county of Macon and State of Illinois, have invented a new, original, and ornamental Design for a Hanger for Light-Reflecting Bowls, of which the following is a specification, reference being had to the accompanying drawing, forming part thereof.

Figure 1 is a side elevation of my im-

proved design. Fig. 2 is a front elevation of the same.

I claim:

The ornamental design for a hanger for light reflecting bowls, as shown.

W. E. SURFACE.

Witnesses:

W. J. GRADY,

HARRY GARVER.
